United States Patent Office.

WILLIAM R. GOODRICH, OF UTICA, NEW YORK.

Design No. 4,310, dated August 30, 1870.

DESIGN FOR COAT AND HAT-HOOK.

The Schedule referred to in these Letters Patent and making part of the same

To all whom it may concern:

Be it known that I, WILLIAM R. GOODRICH, of the city of Utica, in the county of Oneida and State of New York, have invented a new and original Design for a Coat and Hat-Hook, of which the following is a specification.

Nature of the Design.

My design consists—

First, in the ornamentation of the sides of a coat and hat-hook, by recessing the surface of such sides, so as to form one or more panels, thereby leaving the edges of the hook around the panel or panels raised, such raised surface thereby forming a border to such panel or panels.

Secondly, in making the form of the lower or coat-hook to consist of pieces united at an obtuse angle with each other.

Description of Accompanying Drawings.

In the accompanying drawings—

Figure 1 is a side elevation of my cap and hat-hook, showing the shape and configuration thereof.

Figure 2 is a front elevation of the same.

General Description.

This hook is double, (see fig. 1,) being composed of an upper or hat-hook, A, and a lower or coat-hook, B, attached to the under side of the arm A, and braced at its back by a connection with the screw-plate.

The curvature of the hook B is not a circle, but is composed of six or more or fewer straight lines, as C, D, E, F, G, H, &c., thereby forming a section of a pentagon, sexagon, heptagon, or other geometrical

figure, according to the number of straight lines employed.

Both hooks A and B have flat sides.

The surfaces of these sides are ornamented with recessed or sunken panels, as W W, &c.

The surface around these panels is left raised, thereby forming a border, Z, to the panel and edges to the hooks.

The ornamental raised panel K K, &c., and the like, which are in the middle of the sunken panels, and the fluting at the bottom of the sunken panels, may be represented, but is not claimed.

This design does not relate to the general shape of this coat and hat-hook, for that is old, nor to the making of such a hook with flat sides, but to the angular formation of the lower hook, and to the formation of recessed panel-work on the sides of such hook, as heretofore more particularly stated under the definition of the nature of the design.

Claims.

I claim—

1. The design for a coat or hat-hook, with recessed panel or panels, leaving the edges of the hooks around the panel or panels raised, substantially as described and represented.

2. The design for the lower or coat-hook, substantially as shown, viz., as made up of pieces united at an obtuse angle with each other.

WILLIAM R. GOODRICH.
